SUSPENDED EARTH-SHORING DEVICE
Joseph De Lillo, 3 Fulton Place, Jericho,
Long Island, N.Y.
Filed May 27, 1969, Ser. No. 32,290
3 Claims. (Cl. 61—41)

The present invention relates generally to accessory equipment for excavating operations, and in particular to an improved type of earth-shoring device.

In the construction field it is well known that shoring of the side surfaces of a trench or other excavation is required in order to preserve the contours of the trench against the forces of erosion and to allow a man to work in the trench without danger of being injured by a cave-in. A problem is encountered in that the need for shoring increases as continuing work on the trench makes it progressively deeper, and ways must be found of accommodating the shoring device employed to the changing depth of the trench.

Some previous shoring devices sink bodily into the trench as the latter gets progressively deeper. Unless the device originally extends far above the top of the trench, creating a hazardous obstruction, such sinking results in exposure of the upper portions of the trench sides where collapse is most likely and shoring is therefore most important. If on the other hand the shoring device is fixed at the upper portion of the trench wall, some other provision must be made for shoring the deepening lower portion of the trench wall.

It is broadly an object of this invention to provide a solution to the problem of shoring an excavation, and in particular to provide an earth-shoring device which is better able to accommodate itself to the increasing depth of the excavation.

In accordance with an illustrative embodiment demonstrating objects, features, and advantages of invention, there is provided a device for shoring the side surface of an excavation. Such device comprises a member adapted to be supported externally of the excavation. A shoring wall is provided which is shaped to confront the side surface of the excavation so as to contain the latter, and means are provided for suspending the shoring wall from the externally supported member in confronting relationship to the side surface of the excavation. It will thus be appreciated that by suspending the shoring wall from outside the excavation, the shoring wall is prevented from sinking bodily as the depth of the excavation increases, and consequently the upper part of the excavation remains protected. As a further feature of the invention, the shoring wall may include vertically telescoping sections dropping lower as the excavation becomes deeper, thus simultaneously shoring the upper portion of the excavation and automatically extending downward to the extent necessary to shore the deepening lower portion as well.

The foregoing brief summary, as well as additional features of the invention, may best be appreciated by reference to the following detailed description of an illustrative embodiment, when read in conjunction with the accompanying drawings, wherein:

FIG. 1 is a top plan view of a suspended earth-shoring device in accordance with the present invention installed in an elongated trench;

FIG. 2 is a side elevational view of the device of FIG. 1;

FIG. 3 is a front elevational view of one of the opposed shoring walls of the device of the preceding figures; and,

FIG. 4 is a perspective view of a single shoring wall element disassembled from the device of the previous figures, with parts broken away and shown in phantom to reveal the internal structure thereof.

2

Referring in detail to the drawings, there is seen in FIG. 2 an earth-shoring device, generally designated 10, including a pair of cross beams 12 and 14 extending across the mouth of an elongated trench T and a pair of downwardly extensible walls 16 and 18 which are suspended from the cross beams in confronting relationship to the respective opposite side surfaces S of the trench for shoring the latter.

The members 12 and 14 may be any conventional type of beam such as the metal I-beams shown in FIGS. 1-3. These beams are placed across the trench T at locations spaced along the length of the trench. The opposite ends of the beams 12 and 14 rest on the earth on opposite sides of the trench T as seen in FIGS. 1 and 2, to provide firm support therefor and enable them to support the weight of the shoring walls 16 and 18 suspended therefrom.

For suspending the walls 16 and 18 from the beams 12 and 14, there are provided bridging beams 20, 22, 24, 20 and 26, which may also be metal I-beams, secured to the cross beams 12 and 14 by means of bolt and nut assemblies 28 extending through suitable bores in the flanges of the I-beams. A first pair of the bridging beams 20 and 22 are placed in spaced and parallel relationship to each other and positioned on the cross beams 12 and 14 so as to extend bridgingly therebetween directly above one of the side surfaces S and substantially parallel thereto. A second pair of the bridging beams 24 and 26 is similarly placed in relation to the other side surface S. With the bridging beams 20 through 26 thus arranged, the elongated spaces between the paired beams 20 and 22 and between the paired beams 24 and 26 form a pair of mounting channels 29 above the respective side surfaces S through which the respective shoring walls 16 and 18 depend in confronting relationship to the side surfaces.

The shoring walls 16 and 18 are identical, as seen in FIGS. 1 and 3, and each consists of a plurality of wall elements 30 mounted in a row in the channels between the bridging beams 20, 22 and 24, 26, each row forming a broad, flat wall-like structure shaped to face closely against the side surfaces S and thereby shore the latter against collapse. A representative element 30, as seen in FIG. 4, includes three coaxially arranged hollow metal box sections 32, 34 and 36 of appropriately decreasing size to be slidable one within the other for mutually telescoping motion. This enables the inner and lower sections 34 and 36 to slide downwardly relative to the outermost and uppermost section 32 under the influence of their own weight, thus automatically extending the shoring walls 16 and 18 to reach to the bottom of the trench T as the latter becomes progressively deeper. The section 32 is suspended in the mounting channel 29 between bridging beams 20, 22 and 24, 26 and held against descent by tongues 38 which project outwardly from the upper margin of section 32 and abut against the upper surfaces of the bridging beams at both sides of the mounting channel 29. This enables the ready removal of the wall elements 30 from the channels 29 by merely lifting them upwardly therefrom. The middle and lower sections 34 and 36 are retained in assembly with the upper and middle sections 32 and 34 respectively by tongues 40 and 42, the former projecting inwardly from the lower edges of an outer, upper section 32 or 34 and the latter projecting outwardly from the upper edge of an inner, lower section 34 or 36 and being above the tongues 40 to abut thereagainst for limiting the downward travel of the inner, lower sections. The projecting tongues 38, 40, and 42 may be made of small pieces of bar or heavy plate stock welded to appropriate surfaces of the sections 32, 34, and 36. A number of reinforcing partitions 44 are welded in place in the innermost section 36 to lend extra rigidity to the structure. It will be readily appreciated that the

I-beams and partition-reinforced box sections of the shoring device 10 give the latter a relatively high strength to weight ratio, especially if aluminum is chosen as the construction material.

As an additional precaution it may be desired to provide braces extending transversely across the trench T to hold the opposite shoring walls 16 and 18 apart to more effectively contain the side surfaces S. For this purpose a somewhat oversize beam may be forced into place between the shoring walls, or an extendable mechanism such as a screw jack may be expanded against the walls, the tight fit serving to hold the beam or jack in place. In a preferred embodiment of the invention, however, the brace may be suspended between the shoring walls to eliminate the need to hold it in place by a tight fit. A pair of H-shaped structures are each formed of a pair of carrier beams 50, which may be metal I-beams, positioned longitudinally of the trench T and adjacent the respective opposite shoring walls 16 and 18, and cross braces 52, which may also be metal I-beams, welded to the carrier beams adjacent the opposite shoring walls in position to extend therebetween across the trench T. The two H-shaped structures are suspended at different levels within the trench T by chains 54 at the four corners of the H arrangement passing through suitable bores in the inwardly pointing flanges of the bridging beams 22 and 24 and the central webs of the carrier beams 50. Links 56 at both ends and in the middle of chains 54 are made too large to pass through these bores so as to retain the two H-shaped structures at their respective levels. The cross braces 52 are of such a length that the H-shaped structures normally hang freely on the chains 54, relying on the latter to hold them in place rather than on pressure of the shoring walls 16 and 18 thereagainst, but if the latter should begin to collapse inwardly toward each other, then the H-shaped structures become engaged therebetween to buttress the shoring walls against such collapse.

A typical installation of the shoring device 10 may now be discussed in order to demonstrate the ease of handling and using this device. The cross beams 12 and 14 are first set in place across the site of the trench T, and then the outer bridging beams 20 and 26 are bolted in place thereon. Next the assembly of the inner bridging beams 22 and 24 and the H-shaped bracing structures 50, 52, 54 suspended therefrom are bolted in place on the inner bridging beams 22 and 24. At first the suspended bracing structure 50, 52, 54 can be furled up and lashed to one of the cross beams 12 and 14, and then later released to depend into the trench T when the depth thereof has increased sufficiently to accommodate the bracing structure and to warrant its use. Finally, the shoring walls 16 and 18 are installed by inserting rows of the wall elements 30 side by side into the channels 29 between bridging beams 20, 22 and 24, 26. The walls 16 and 18 will be prevented from extending by the shallow bottom of the trench T as excavation is first begun, but as the trench deepens progressively with continued excavation, the lower sections 34 and 36 of each wall element 30 will slide downwardly out of the upper sections 32 under the force of their own weight. The tongues 40 and 42 define positions of maximum extension therefor to retain the telescoping sections 32, 34, and 36 in assembly, and the entire element 30 is limited in its descent through the channel 29 by tongues 38 which suspend the wall elements from above to assure that they will extend rather than collapse and sink bodily into the deepening trench T. Thus, as the excavation work proceeds, the shoring de-

vice 10 will at all times cover both the upper part of the sides S and as much of the lower part thereof as has so far been excavated, and as the device extends far into the earth it will automatically be braced against collapse if the earth begins to cave in against it. When no longer needed, the device 10 can be disassembled and removed from the excavation, by simply reversing the installation process, and used over again in other excavations as often as necessary.

It will now be readily appreciated that the present invention provides a light but strong earth-shoring device which is suspended to prevent it from sinking into the excavation as the latter becomes progressively deeper, and which extends automatically to accommodate itself to the increasing depth, thus assuring simultaneous support of both the top and bottom portions of the excavation at all stages of the work. In addition, there is provided a brace structure which does not need to be compressed between the opposite walls of the shoring device to maintain it in place, but which hangs freely in place, ready to automatically exert the proper amount of buttressing force on the shoring walls to the extent they be forced inwardly by pressure from the sides of the excavation.

The particulars of the foregoing description are intended to be illustrative rather than restrictive, and are subject to a considerable latitude of modification without departure from the novel teachings disclosed herein. Accordingly, the scope of this invention is intended to be limited only as defined in the appended claims, which should be accorded a breadth of interpretation consistent with this specification.

What I claim is:

1. A device for shoring the side surfaces of an excavation comprising a pair of cross beams adapted to extend across the mouth of an excavation with the opposite ends of said beams extending substantially beyond the opposite sides of the excavation to provide support for the suspension of shoring elements, a pair of bridging members extending between said cross beams and being supported thereby within the mouth of an excavation, a plurality of vertically telescoping sections adapted for gravitational elongation into the excavation as the same becomes deeper, said sections being tubular in form and rectangular in cross-section and jointly comprising a shoring wall adapted for suspension from said bridging members in confronting relationship to the side surfaces of the excavation, and means at one end of said telescoping sections releasably engaging said bridging members comprising means for suspending said sections in contiguous order along the wall of the excavation.

2. The device of claim 1 in which said bridging members consist of a pair of spaced beams forming therebetween a channel adapted to accommodate said telescoping sections.

3. The device of claim 1 in which said bridging members consist of a pair of spaced beams forming therebetween a channel adapted to accommodate said telescoping sections, and said means for releasably engaging said bridging members comprises abutments extending laterally from said telescoping sections in abutting relation to said beams at opposite sides of said channel.
